(57) **CLAIM**

The ornamental design for a LED headlamp, as shown and described.

DESCRIPTION

FIG. 1 is a rear, right perspective view of the LED headlamp;

FIG. 2 is a front, right perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof; and,

FIG. 9 is another rear, right perspective view thereof, shown in an alternate configuration of use.

The broken lines shown on the drawings depict portions of the LED headlamp that form no part of the claimed design.
